UNITED STATES PATENT OFFICE.

WILLIAM VOGLER, OF SOMERVILLE, MASSACHUSETTS.

GARMENT-STAND.

SPECIFICATION forming part of Letters Patent No. 445,208, dated January 27, 1891.

Application filed May 31, 1890. Serial No. 353,823. (No model.)

To all whom it may concern:

Be it known that I, WILLIAM VOGLER, of Somerville, county of Middlesex, State of Massachusetts, have invented an Improvement in Garment-Stands, of which the following description, in connection with the accompanying drawings, is a specification, like letters and figures on the drawings representing like parts.

- 10 This invention has for its object the production of a stand to support and stretch pantaloons. I also prefer to provide the stand with an extension or top having a coat-support.
- 15 Figure 1 in elevation represents a garment-stand embodying my invention; Fig. 2, a section below the line x ; Fig. 3, a section below the line x' , and Fig. 4 shows a modified form of leg-holder.
- 20 The standard a has feet a' to stand on the floor. The feet are composed of rods pivoted at 2 to ears of a collar b , secured to the lower end of the standard, the outer ends of the feet having jointed to them at 3 links b' , in turn jointed at 4 to ears of a collar or runner b^2 , made adjustable on the said standard, so that by moving the collar b^2 toward the collar b the legs may be folded, as when it is desired to pack the stand. The standard a at or near 25 its upper end is screw-threaded, as at 6, to receive upon it a shouldered nut c^x , on which is loosely mounted the two-part cross-bar c of the two-part clamp $c c'$, the bar c' receiving through it loosely the screw-studs c^2 , on which 30 are screwed the thumb-nuts c^3 , when it is desired to clamp the waistband of the pantaloons P in the clamp. The shouldered nut has a thumb-piece 10, by which it may be rotated to move the clamp longitudinally on the standard. Below the clamp $c c'$ the standard has mounted on it a bottom bar d , which may be held in place by a set-screw d' , the said 35 bar being passed through a hole or slot in a collar d^2 , which may be held in place when desired by a set-screw d^3 . The bar d has, as shown, two adjustable collars or arms $e e'$, which are jointed to blocks or leg-holders e' , adapted to enter the pantaloons-legs, the said blocks, as shown, being adjustable as to their

50 diameter by right and left threaded screws 50 12, the blocks being provided at their peripheries with pins or projections to enter the pantaloons. When the waistband is clamped and the blocks engaged with the lower ends of the legs of the pantaloons, the shouldered 55 nut may be turned, thus moving the clamp longitudinally to stretch the pantaloons.

The top of the nut c^x has screwed into it an extension f , on which is mounted or supported a coat-holder g , and at its top the extension is shown as provided with a ball h for a hat.

A stand of the kind described will hold a suit of gentlemen's clothes and keep them in proper shape.

I do not desire to limit my invention to the exact form or construction of the feet.

In the modification, Fig. 4, the two parts 22 23 of the leg-holder are attached to a threaded stem 24, and are adjustable thereon, the screw 70 24 being equivalent to the screw 12.

I claim—

1. A holding-stand for gentlemen's clothing, it being composed of a screw-threaded standard having feet, a shouldered nut rotatable on the threaded part of the said standard, a two-part clamp-bar mounted loosely on the said nut, a bottom bar, and leg-holders to engage and hold the legs of the pantaloons, substantially as described.

2. A holding-stand for gentlemen's clothing, it being composed of a screw-threaded standard having feet, a shouldered nut rotatable on the threaded part of the said standard, a two-part clamp-bar mounted loosely on the said nut, a bottom bar, and leg-holders to engage and hold the legs of the pantaloons, the rod f , mounted on said shouldered nut, and a coat-support sustained by said rod above the said clamping-bars, substantially as described.

In testimony whereof I have signed my name to this specification in the presence of two subscribing witnesses.

WILLIAM VOGLER.

Witnesses:

GEO. W. GREGORY,
EMMA J. BENNETT.
